US00D619964S

(12) **United States Design Patent**
Coushaine et al.

(10) **Patent No.:** US D619,964 S
(45) **Date of Patent:** ** Jul. 20, 2010

(54) **LIGHT EMITTING DIODE BULB
CONNECTOR**

(75) Inventors: **Charles M. Coushaine**, Rindge, NH (US); **Kim Albright**, Warner, NH (US); **Thomas Tessnow**, Weare, NH (US)

(73) Assignee: **Osram Sylvania, Inc.**, Danvers, MA (US)

(**) Term: **14 Years**

(21) Appl. No.: **29/261,348**

(22) Filed: **Jun. 13, 2006**

Related U.S. Application Data

(63) Continuation of application No. 11/109,917, filed on Apr. 20, 2005, now Pat. No. 7,092,612, and a continuation of application No. 11/058,304, filed on Feb. 16, 2005, now Pat. No. 7,110,656, and a continuation of application No. 10/838,090, filed on May 3, 2004, now Pat. No. 7,059,758, and a continuation of application No. 10/830,261, filed on Apr. 22, 2004, now Pat. No. 7,075,224.

(57) **CLAIM**

The ornamental design for a light emitting diode bulb connector, as shown and described.

DESCRIPTION

The FIGURE is a perspective view of a light emitting diode bulb connector showing our new design.
